CLAIM

The ornamental design for a plant caddy with hidden wheels, as shown and described.

DESCRIPTION

FIG. 1 is a top perspective view of a plant caddy with hidden wheels showing my new design;

FIG. 2 is a bottom perspective view of FIG. 1;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of portion 9 in FIG. 2.

The long dash-short dash broken lines indicate cutoff boundaries for enlarged detailed portion views and form no part of the claimed design. The portions of the plant caddy with hidden wheels shown in broken lines form no part of the claimed design.
